MERCHANDISING DISPLAY STAND

Frank H. Stephens, Jr., 2646 Cove Circle NE., Atlanta,
Ga., and Thaddeus I. Kingsford, 3215 Embry Circle,
Chamblee, Ga.

Filed Apr. 6, 1965, Ser. No. 84,640

Term of patent 14 years

(Cl. D80—9)

FIG. 1

FIG. 4

FIG. 5

FIG. 2

FIG. 3

FIG. 6

FIG. 1 is a perspective view of a merchandising display stand for lighters, writing instruments and the like showing our new design, said stand being adapted for lighters;

FIG. 2 is an enlarged front elevational view of FIG. 1;

FIG. 3 is an enlarged top plan view of FIG. 1;

FIG. 4 is a right side elevational view of FIG. 1;

FIG. 5 is a rear elevational view of FIG. 1;

FIG. 6 is a perspective view of an alternative of the stand as adapted for writing instruments.

The dominant features of the design reside in the portions shown in full lines.

We claim:

The ornamental design for a merchandising display stand, substantially as shown and described.
